UNITED STATES PATENT OFFICE

RALPH A YELLI, OF LOS ANGELES, CALIFORNIA, ASSIGNOR OF ONE-FIFTH TO
H. MISCHLER, OF LOS ANGELES, CALIFORNIA

AIRSHIP

Application filed January 29, 1929. Serial No. 335,844.

This invention relates to improvements in airships or in lighter than air craft and more particularly to propulsion and steering means therefor.

5 One of the objects of this invention is to provide improved means for providing a simple, efficient and inexpensive mechanism for maintaining the stability of an airship, and for keeping it to an even keel when in 10 the course of flight.

Another object thereof is to provide an air tunnel in the airship with means for creating a suction therein as a means of propelling the airship, means being also provided for 15 the purpose of directing and controlling the direction in which the aircraft is propelled.

Another object of this invention is to create a supplementary source of air suction in the front of the ship for assisting in sucking air 20 thru the tunnel and for causing better stabilization of the airship when in flight.

Another object thereof is to provide means for varying the volume of suction at the front end of the airship, thus changing the rate as 25 well as the duration of suction thru the air tunnel and at the same time counterbalancing undue pressure exerted thru atmospheric conditions on any particular part of the ship that might otherwise tend to make it deviate 30 from a set course.

A further object of this invention is to provide an airship with regulating means for varying the suction in the air tunnel at the front inlet end of the machine whereby to 35 allow for righting any tendency on the part of the ship to pitch or lose even keel.

Another object of this invention is to provide a series of divergent air shafts at the inlet end of the main air tunnel extending 40 from the front to the rear of the airship in which air may be sucked thru the air shafts into the tunnel in angular lines, and by means of which air communication between any air shaft may selectively be stopped to better 45 stabilize the airship.

A further object of this invention is to provide propellers or propulsion means in conjunction with the several air shafts for the 50 purpose of sucking as well as exhausting air therethru and from the tunnels, and for the

purpose of creating a draft in the air conduit to be conveyed into the tunnel to draw air out of the tunnel.

Another object of this invention is to provide a steering wheel designed to be operated by the pilot or director of the airship and effective to control the suction of air thru the air shafts collectively or separately as may be desired.

Another object of this invention is to establish intercommunication between all of the air shafts with the main air tunnel whereby to allow all or none of the air shafts to simultaneously function to suck air out of the tunnel from front to the rear thereof.

Another object of this invention is to provide a series of trap doors in the several air shaft branches of the main airship air tunnel, each trap door controlling and regulating the passage of air thru one particular and different air shaft, and from it into the tunnel.

Another object of this invention is to provide means for the purpose of providing a unitary steering wheel for selectively operating the means for establishing simultaneous intercommunication between all of the air shafts and the tunnel, and for selectively and interchangeably operating any single trap door to the exclusion of the other for opening the air line of communication between this air shaft and the main tunnel.

A still further object of this invention is to steer the airship by means of the inlet air conduits or shafts formed as terminals upon the main air tunnel to the extent that by closing the air line communication between all but one of the air shafts suction taking place in the particular air shaft open will cause air pressure and air force in this open air shaft to direct the ship in the direction of location of the open air shaft thereby veering the airship about this point of change of direction.

And another object of this invention is to provide four air shafts, two being arranged in a vertical plane, and two at right angles thereto for the purpose of pointing east, west, north and south, to regulate by the trap doors

in these air shafts the point where the airship is to veer and change its course.

With the above and other objects in view my invention consists in the combination, arrangement and details of construction disclosed in the drawings and specification, and then more particularly pointed out in the appended claims.

10 In the drawings, wherein similar reference characters designate similar parts throughout the respective views,

Figure 1 is a side elevation of my invention of airship,

15 Figure 2 is a front elevation of the air shafts, showing partly in section, the operating means,

Figure 2a is a fragmental sectional detail view of an air shaft showing the means of operating the trap door therein,

20 Figure 2b is a view similar to Figure 2 and showing the trap door in open position,

Figure 3 is a front end elevation of part of the airship,

25 Figure 4 is a fragmental sectional detail view of a tunnel joint,

Figure 5 is a longitudinal sectional view taken thru the air tunnel,

30 Figure 6 is a fragmental sectional elevation taken of the front end of the tunnel, showing the air shafts,

Figure 7 is a fragmental detail view of the rotary valve shown in moved position relatively to Figure 6,

35 Figure 8 is a top plan view of the steering wheel and dial there opposite,

Figure 8a is a sectional view of the tunnel showing an end view of the rotary valve therein controlling the flow thru the air shafts,

40 Figure 9 is a front elevation of the air shafts showing the trap door actuating means,

Figure 10 is a front elevation of the upper air shaft,

45 Figure 11 is a fragmental front view of the four air shafts,

Figure 12 is a front elevation of the left central air shaft,

50 Figure 13 is a front elevation of the four air shafts showing the means for actuating the rotary valve,

Figure 14 is a front elevation of the lower central air shaft, and

55 Figure 15 is a fragmental sectional elevation of the four air shafts showing the rotary plug open to connect with all of them.

60 In the drawings, which are merely illustrative of my invention, an airship is shown in most respects being of conventional construction as concerns the construction of the body for holding the lighter than air gas. The main body of this airship is designated 10 and extending thru the center of this body longitudinally from front to rear is a tunnel or wind conduit 11 which at the center

of the body is broken where blowers soon to be described are found.

A series of struts or girders of any approved construction is provided and is designated 13 for supporting the longitudinal tunnel and at the same time bracing the upper and lower portions of the body; each strut may have the oppositely extending or forked terminals 14, 15 where it joins the upper or lower portions of the body 10 of the airship. Connected longitudinally underneath the main body portion 10 of this airship is a compartment 16 which houses the crew, cargo, passengers and others, suitable doors 19 being provided, for exit and entrance, and suitable windows being also provided, the carriage body having the traction and landing wheels 18 as shown. At the rear of the airship the body 10 tapers as at 20 and carries the rudders 21, 22 and other parts that an airship requires for helping in the steering function. The rear struts 23 are designed to reinforce the tapering portion of the body 20 and it will be seen that this tunnel has its section 12 open out of the airship at the rear thereof.

My invention has to do with the front of the airship where a suction device is installed for steering and for stabilizing the airship when in flight. For this purpose there are provided a plurality of separate air shafts, four in number preferably, designated 24, 24a, 24b, and 24c, arranged, two air shafts 24, 24b, in a vertical plane, and two air shafts 24a, 24c arranged in a horizontal plane, so the respective air shafts point northeast, southwest, and northwest and southeast respectively. These air shafts connect operatively with the adjacent front end of the tunnel 11, 12 for sucking air out of the tunnel and the air shafts may be constructed in different ways.

For example it may be desired to cause the air shafts which are in the form of tubes, to rotate themselves so in Figure 1 these air shafts are held against longitudinal movement in fixed collars or bearings 23 arranged radially from the tunnel 11 to cause the air shafts to project divergently at the front part of the airship. The propellers 29 are inside the flaring funnel shape ends 30 of the air shafts, and are fixed so as to rotate with the air shafts. The mechanism for rotating the air shafts may be any suitable device or engine, the gearing 27 in the form of rings being suitably operated thru a separate motor for every air shaft. The inner ends of the divergent air shafts are operatively connected and made to communicate with the air tunnel 11. In Figure 4 it will be seen that the tunnel 11 has a miter-shaped portion 30a formed at its extreme front end, whereby four branch stems are provided, two, 32, in a horizontal plane, and two, 33, in a vertical plane, or vice versa. However in Figures

6 and 7 the conduits of air shafts 24, 24a, 24b, and 24c are connected without the miter portion, to the tunnel.

It is particularly designed to keep the front 5 end P of the tunnel 11 open at all times for the permanent reception of air, save when repairs are being made to this tunnel. This assures that air can enter thru the front end of the airship and be exhausted thru the rear 10 thereof. However, where the wind shafts are employed each is to have its air supply or air passage separately controlled. Packing rings or the like 34 may be interposed between the stems of the joint 30a and the adjacent 15 ends of the wind shaft to prevent leakage of air there around.

Instead of rotating the air shafts directly they may be made stationary as shown in Figure 6. The four air shafts will diverge 20 forwardly of the airship, with two being arranged in a vertical plane and two in a horizontal plane, preferably. A rotary valve or plug 35 is located at the fore end of the air tunnel 11 and is formed with four 25 right angularly separated ports or holes A, B, C and D for registering and communicating, if need be, with the bores of the four air shafts, 24, 24a, 24b, and 24c. This valve 35 has an axial bore 36 extending therethru 30 from one end to the other thereof with the optional flaring inlet T and the four radial ports A, B, C, and D communicate with this axial bore; this axial bore 36 opens out to the atmosphere at all times as at P. This plug 35 valve is carried rotatably by a large gear 35a 35 interposed between sections of the tunnel 11, with suitable packing therebetween, if desired, it being also understood that this tunnel can be supported by the struts 13. The 40 gear 35a has a central opening 36a for the passage of air thru the tunnel. The gear 35a is connected thru a sleeve 47 to another toothed wheel or gear 48 this sleeve being revolvably mounted upon the tunnel 11. Meshing with this gear 48 is a smaller gear 49 operatively supported in any position and in any bearing in the airship. The shaft 50 has fixed thereon a sprocket wheel (not designated) and trained upon this wheel is a 55 sprocket chain 51 also trained upon the sprocket on a stub shaft 52 mounted in the fixed bearings 53 and carrying the steering wheel 54, which is arranged to turn against a fixed segmental scale 55 having inscribed thereupon a series of consecutive numerals 1 to 6 inclusive, preferably extending from right to left. By turning the steering wheel gear 48 is rotated, which thru the sleeve 47, turns the wheel 35a which is formed at diametrically opposite points with rows of teeth, 62, and 63, the balance of the peripheral edge of this wheel being void of teeth. Operatively mounted in bearing lugs 44m 60 carried externally from the tunnel 11 are the shafts 48', and upon each of these shafts

is fixed a pinion, four pinions being shown, designated respectively 42, 43, 44 and 45. In Figures 7 to 13 inclusive an alternate construction of wheel is shown, wherein the wheel and valve are combined in the unitary structure 35, having the diametrically opposite rows of teeth 62 and 63 formed thereupon.

An alternate form of suction device for the air shafts is disclosed in Figure 6 where on shafts 39, journaled in diametrical bearings 30, if desired secured in the air shafts severally, and rotated thru any instrumentality that may include a motor, are propellers 38 which may consist of four blades as shown in Figure 2.

These propeller blades are made greater in length than the bore of the air shafts so as to create a strong suction. The air shafts may each be divided longitudinally into two 33 separate air compartments 40, 40a, the partition 24m providing these two separate passages or compartments in each air shaft, the latter being so arranged and proportioned that any of the ports A, B, C, or D of the 38 rotary valve 35 will or may register with any of these passages 40, 40a of any selective air shaft. This form of construction and arrangement of the parts are all optional. The 43 passages 40 of the several air shafts will make 39 communication thru the ports 41, one for each air shaft, with the main passageway 36 of the tunnel itself. In Figures 2a and 2b the air shafts are not shown formed with any partitions and here there is just one bore 40. Operatively slidable in the passage 40 of the air shafts are the trap doors designated respectively 56, 56a, 56b and 56c. A diagonally disposed slit, is formed (Figures 2a and 2b) so as to intersect the passage 40, as the case 48 may be, and a notch 57 is formed diametrical- 53 ly opposite the slit to receive one end of the particular trap door. Located in the slit 58 is a coiled spring 60 confined in this slit by the cap or like member and constrained to apply spring pressure against the outer end of the trap door 56 to keep it in closed position so air cannot possibly pass thru the passage 40 of the air shaft in question as long as this trap door is closed. Each trap door 58 has a stem 59 by means of which the trap door can be pulled to open position to unbar the passage 40.

In Figure 6 it will be seen that the slidable trap doors 56, 56a, 56b, 56c are connected to coiled springs 57b which restore them to normal position after they may have been ex- 63 tended. These valves have their inner ends closed upon the bearing blocks 57a, located in the 68 passages 40.

It will be seen also that the air shaft pas- 73 sages 40a register with the ports 41a formed in the front, flaring end of the main tunnel 11 so as to communicate with the ports A, B, C and D of rotary plug 35. Formed in the 78

flaring part of bore 36 are four ports S by means of which air may be sucked in, thru any of the passages 40, thru port 41, and by way of the port S into the tunnel 11, when a particular trap door 56 is open for this purpose.

The pinions 42, 43, 44 and 45 on shafts 48' carry suitable wrist pins 62 to which is attached at one end a flexible element such as a string 61 which is attached also to the outer end of one stem 59 or other part of one trap door 56. Referring now to Figures 7-13 inclusive it will be seen that the four pinions are spaced apart circumferentially of the wheel 35a. One pinion 42 is arranged at the upper dead center position of the wheel 35a; the one just below it, designated 43 is spaced away a short distance below dead center; the pinion 44 is located midway dead center position; while the pinion 45 is spaced therebelow a short distance.

It will be understood that where the propellers are located inside the air shafts as shown in Figure 1 four blades will preferably be connected to their shafts severally. In Figure 5 the struts consist of triple units, the center unit being perpendicular, designated 13c, while the adjacent struts incline in opposite directions as at 13a, 13b, but converge in sets or pairs from the tunnel 11 towards the outer walls of the tunnel.

The means for creating a suction thru the main tunnel 11 are suitable blowers, powerful in effect and of any approved design. Two sets of blowers are provided, designated 64 and are operatively supported centrally of the machine, one set being used only in cases of emergency should the other set be crippled or otherwise disabled. The tunnel 11 is divided, as already stated, into two sections, each section terminating in outwardly diverging stems; one section has the fork with the stems 65, which connect thru the tubes 65a from the operating set of blowers 64, to the inactive set of blowers 67, while the other fork having the stems 66a lead from the operating blowers to the inactive blowers so air generated by the operating blowers and effective to create a suction is forced thru the inactive blowers into the section of the tunnel that extends to the rear. In this manner the air thru the tunnels may be sucked out. It will also be understood that the entire length of the airship will be divided by bulkheads into separate compartments, each to be filled preferably with helium gas. The body or envelope 10 is spacious enough to provide quarters for the various operators of the craft.

In operation the airship is built along lines of speed. The blowers when in full operation will suck air in from the front end of the airship to the extreme rear and the air will initially come in from the open front end of the tunnel and exit thru the open rear end

thereof. This creates a vacuum or partial vacuum at the front or nose end of the machine and as this vacuum causes a forcible inrush of air from rear to front, where the vacuum exists, the airship is impelled on its forward course in a straight line.

As each of the propellers at the front of the machine and associated with the air shafts which connect with the air or main tunnel rotates, it also creates a suction in front of the machine and also inside of the air shafts it sends air into the tunnel which passes from front to the rear of the machine; in this aspect the propellers 38 or 29 will supplement the action of the blowers in sucking air into the airship so the speed of the craft is increased considerably. In this capacity, the air shafts will allow air to enter the tunnels, when trap doors are severally open, and thus pass into the tunnel 11 but at no time is it designed to open all trap doors at the same time.

The propellers will direct air in advance of the craft towards the center of the airship nose and thru the respective branch tunnels from which the air is forced into the main tunnel and will ultimately be discharged from the latter at the rear of the craft, thus causing the ship to be propelled forwardly thru the atmosphere as a result of the partial vacuum created in advance of the craft. Stability of the airship is also increased as the several wind shafts each exerts an influence of equilibrium as they point to north, south, east and west at the same time and frustrate any tendency on the part of the aircraft to pitch or list in any manner.

The airship can be steered by cutting out, or by closing the trap doors of all but one of the propellers, the remaining propellers in operation, acting to draw the nose of the craft laterally, the tail end of the craft being steered by the usual elevators and rudders forming no part of this invention, thus aiding the propellers remaining in operation in the steering function.

In operation the steering wheel 54, in the hands of the ship's operator can be caused to control all of the trap doors of the four air shafts 24, 24a, 24b, 24c; or he can thru the same steering wheel open any selective predetermined trap door of the particular air shaft or else open all of the ports.

Thus by moving the indicating mark 56a on the steering wheel to numeral 1, on scale 55 (Figure 5) the valve 35 is brought into the position shown in Figure 9, with ports A, B, C and D out of registration with the passages 40a of the air shafts, as the case may be; hence no air can enter the tunnel thru the air shafts as the trap doors 56 are all closed at this time. By moving the wheel counter-clockwise still further with indicating mark registering with numeral 2, the ports A, B, C, and D of valve 35 register with all four

air shafts so air can be transmitted from propellers 38 into the tunnel, (as shown in Figure 11). When the wheel 54 is moved to bring mark 56a' into registration with numeral 3, the row of teeth 62 on the wheel 35a will mesh with pinion 42, resulting in one trap door 56 controlled by it being operated as shown in Figure 13; as the wrist pin 62 on this gear turns from the normal position (with trap door 56c closed) to its position as shown in Figure 2b, the string 61 pulls trap door to open position, and by locking the steering wheel 54 in this position, by means not shown, the trap door can be held open and will remain open. When steering wheel moves to register mark 56a with numeral 4, the teeth 62 will mesh with pinion 43, and now a different trap door 56 will in the manner already explained selectively be operated and opened; the next turn to numeral 5 made by wheel 54 will not operate any trap door for now the four ports A, B, C, and D will all be open as in Figure 15. So connecting wheel 54 with either numerals 1 or 4 effects the opening of all ports of the valve 35. The moving of wheel to numerals 6 and 7 of the scale will also respectively open the other two remaining trap doors 56a, 56b, as follows; the teeth 62 will mesh with pinion 44 when it leaves its position shown in Figure 15 and thereafter leaves this position and turns pinion 45. I do not limit myself to the exact details of construction herein disclosed but claim all variations falling within the purview of the appended claims. For example, in one figure the valve 35 is formed with the radial tapering connecting ribs and in another view it flares and has wide spaced apart arcuate ports. In both cases the object is to allow constant communication between this valve and all the ports 41.

What I claim and seek protection on is as follows:—

1. An airship having a thru air tunnel extending from the front end clear to the rear end thereof, means for exhausting air from said tunnel, a plurality of interconnected inlet conduits operatively connected to said tunnel at the front end of the airship, means for separately opening the several inlet conduits to the suction of air, suction creating means associated with each inlet conduit, and a unitary controller for the conduit opening means.
2. An airship having a thru air tunnel extending from the front end clear to the rear end thereof, means for exhausting air from said tunnel, located midway the length thereof, a plurality of angularly disposed inlet conduits connected in common to said tunnel at the front of the ship, means for exhausting air from each separate conduit, means controlling passage of air thru each separate conduit, and manually controlled means for operating selectively the air controlling means.

3. An airship having an air suction tunnel extending from end to end thereof, a plurality of outwardly diverging air conduits projecting from said tunnel at the front of the ship, trap doors severally disposed in said conduits, means for separately opening said trap doors, and a device manually operated for selectively and predeterminedly actuating the trap door opening means. 70

4. An airship having air suction means, a longitudinally disposed tunnel in said airship, a pair of air conduits connected to said tunnel at the front of the airship in a vertical plane, a pair of air conduits connected at right angles to the first pair and also connected to said tunnel, an operating wheel, and means controlled by said wheel for selectively closing one or more of said air conduits. 75

5. An airship having an air suction tunnel extending therein from one end to the other, a series of tunnel terminals extending in angular radial relation to said tunnel at the front of the ship, means for sucking air thru said terminals independently of air suction in the tunnel proper, and means for selectively regulating the suction of air into any one of said tunnel terminals. 80 85

6. Stabilizing means for airships consisting of a suction tunnel extending in the airship from end to end thereof, a series of upwardly and outwardly inclining conduits forming terminals of said tunnel at the front end of the airship, said conduits being arranged in a forwardly diverging position, and mechanism manually operated to open selectively any of said conduits for suction purposes to impel the airship in the direction pointed to by the conduit opened to suction. 90 95

7. An airship consisting of a longitudinally extending suction tunnel, means for sucking air from said tunnel to propel the same, a series of divergent conduits communicating at their rear ends with said tunnel and projecting forwardly of the airship, separate propellers associated with said conduits for exhausting air therethru, trap doors in the several conduits, separate means for opening said several trap doors, and rotary means for selectively operating any of said trap doors. 100 105

8. An airship having suction propelling mechanism including an exhaustible central longitudinal tunnel extending from end to end thereof, a plurality of outwardly and angularly disposed conduits, means for separately rotating each conduit relatively to the tunnel, a propeller fixed upon each conduit and rotating therewith, a valve in said tunnel establishing communication with all of said conduit, means in each conduit controlling the passage of air therethru, and unitary means effective to actuate said valve or said air controlling means interchangeably. 110 115

9. An airship having a suction tunnel, air suction means for exhausting air from said tunnel, a plurality of air suction conduits con- 120 125

5 connected to said tunnel at one end of the ship, propellers associated in the inlet ends of said conduits, air regulators carried by said conduits severally, a rotary valve operating in
10 said tunnel and having ports registering with each conduit separately, means for operating said valve, means for separately operating the air regulators, means for causing the valve operating means to operate in time with the air regulator operating means, and manually controlled means for selectively actuating the timing means.

15 10. In an airship, the combination of a suction tunnel formed at one end with outwardly diverging conduits providing separate air shafts, trap doors disposed in the several air shafts, propellers rotatably sucking air thru said air shafts into the tunnel, means for opening and closing said trap doors selectively, and means for simultaneously opening or closing all of said trap doors.

20 11. In an airship having a thru suction tunnel, a plurality of four air shafts formed terminally upon said tunnel, two in a vertical plane, and two in a horizontal plane, means for establishing communication between the tunnel and said air shafts, means operating independently of said other means for selectively closing any of said air shafts from air 25 communication with said tunnel, and mechanism causing the two aforementioned means to act in time.

25 12. In an airship having a suction tunnel, four air shafts connected terminally with said tunnel angularly thereof, and having inlet mouths disposed externally of the airship, propellers rotating in said inlet mouths, means for rotating said propellers separately, means located in the suction tunnel for opening communication between tunnel and all 30 conduits, and means external to the tunnel for selectively opening one conduit at a time for communication with the tunnel and closing the remainder.

35 13. In an airship having suction mechanism of propulsion, an air inlet device having branch conduits, two being arranged vertically and two horizontally in front of the ship, means for independently rotating each 40 conduit, propellers fixed in the several conduits to rotate therewith, a four-way joint carried by said tunnel for establishing communication between the tunnel and each separate conduit, valves associated with each conduit, a valve mounted movably in said joint and having four ports connectible with the four conduits for closing or opening communication therebetween, rotary means for operating the last-named valve, and means 45 actuated by said rotary means for operating the other valves.

45 14. In combination, in an airship, a plurality of radially separated air shafts, a joint common to all of said air shafts, a valve associated with each air shaft for closing com-

munication between it and the joint, a rotatable valve in said joint having ports for communication with the several air shafts simultaneously, and mechanism for interchangeably and selectively operating the rotatable valve and the air shaft valve.

50 15. In combination, in an airship, a continuous air tunnel, a plurality of four air shafts branching out at the front of the ship from said tunnel, and pointing in varying radial positions, said air shafts communicating with the air tunnel at their inner ends, means carried by said tunnel for regulating the admission of air into all of said air shafts simultaneously, and means controlled by the last-named means for regulating the passage of air from air shafts into tunnel selectively, one at a time.

55 16. In an airship, in combination with an air tunnel, branch air shafts diverging out from one end thereof, a rotary plug valve in said tunnel having four ports connecting with an axial central port in line with the tunnel, which ports are connectible with the bores of the air shafts simultaneously, a slideable trap door in each air shaft, springs normally closing each trap door in its conduit, means pulling the trap doors selectively outwardly to open the air line in the conduit, unitary means for selectively actuating one pulling means at a time, mechanism for moving the rotary plug valve, and means controlled by said mechanism for actuating the unitary means.

60 17. In an airship, the combination of a scale having numerals inscribed thereupon, a steering wheel, a steering column for said wheel, an air tunnel having radial branches forming separate inlet air shafts, trap doors in the several air shafts controlling communication between trap door and tunnel, means in said tunnel opening or closing simultaneously the outlet ends of the air shafts into said tunnel, means controlled by said steering wheel for operating said last-named means, and means also controlled by said steering wheel for actuating any of the trap doors selectively.

65 In witness whereof he has hereunder set his hand this twenty-seventh day of December, 1928.

RALPH A. YELLI.
